UNITED STATES PATENT OFFICE.

CHARLES OSCAR MORLOCK AND AXEL NORD, OF VANCOUVER, BRITISH COLUMBIA,
CANADA.

CHESTERFIELD BED.

Application filed August 2, 1922. Serial No. 579,201.

To all whom it may concern:

Be it known that we, CHARLES O. MORLOCK and AXEL NORD, citizens of the Dominion of Canada and of the United States, respectively, residing at Vancouver, in the Province of British Columbia, Canada, have invented certain new and useful Improvements in Chesterfield Beds, of which the following is a specification.

10 This invention relates to a Chesterfield couch having a frontal extension therefrom, extending the width of the lounge seat to form a bed.

In the usual application of a bed extension to a Chesterfield couch, the essential feature of the Chesterfield, viz, the deep upholstering of the seat, is sacrificed in order to enable the bed extension to be concealed within the couch.

20 As will be seen in the following specification, we have retained the customary framework of a Chesterfield couch and have provided a bed that is collapsible to pass under the limited depth between the couch frame 25 and the floor, and have made the seat cushions separate from the upholstering of the seat that the cushions may be used to form a mattress for the bed, when the same is withdrawn and uplifted.

30 Further, the design is such that the bed extension as used in a new Chesterfield bed may be applied to an existing Chesterfield couch with only slight modification of the same.

35 The particular means by which this desirable result is attained is fully set forth in the following specification, reference being made to the drawings by which it is accompanied, in which:

40 Fig. 1 shows in perspective the Chesterfield couch with the bed extended therefrom.

Fig. 2 is a cross section through Chesterfield and bed in the extended position.

45 Fig. 3 is a similar view showing the bed contracted within.

Fig. 4 is a cross section to an enlarged scale of the roller guideway secured to each end of the Chesterfield.

50 Fig. 5 is an enlarged detail of the connection of the head and foot frames to the bed frame.

Fig. 6 is a front elevation of the bed extension frame.

55 Fig. 7 is an enlarged detail of one end of the same partly closed.

Fig. 8 is a plan of the same.

Fig. 9 is a cross section to an enlarged scale of the bed frame on the line 9—9 in Fig. 6.

Fig. 10 is a view of the inner side of a portion of the longitudinal side of the couch, showing the rails of the bed frame and their withdrawing handle in the concealed position.

Fig. 11 is a cross section of the same showing the handle withdrawn as for use.

In these drawings 2 represents a Chesterfield couch of usual construction, in which 3 is the front rail and 4 the back rail of the seat, which rails are connected together at each end by cross rails 5. The seat cushions 6 of the Chesterfield resting on the upholstering above the rails 3 and 4 are removable and are inverted to form the upholstering of the bed extension to be described. 75

On each end rail 5 a member is secured which may be of wood as shown or bent from thin sheet metal in which is a guideway 7 shown in profile in Fig. 2 and in cross section in Fig. 4. Towards the after end this guideway has an upward inclination at 8.

The extension bed frame consists of upper and lower open rectangular frames of angle iron 10 and 11, the upper frame 10 being less 85 in length and breadth than the lower frame 11 that the downwardly turned edge of the upper may enter the upwardly turned edge of the lower frame 11.

The leg ends of a supporting frame 12 90 are pivotally connected at 13 to each end of the lower frame 11, and at 14 are pinned to the ends of frames 15, which form the head and foot of the bed. These ends project upward between the longitudinal 95 rails of the upper frame 10 and are connected at 14 beneath that frame.

The hinge member of 14 preferably has a stop 16 limiting downward movement of the head frame and foot frame 15 at the 100 angular position shown in Fig. 5.

With this construction as the head and foot frames 15 are drawn upward and outward to the position indicated in Fig. 6, the leg ends 12 move to the upright position, 105 lifting the upper frame 10, and the head and foot frames 15 project angularly beyond the ends of the upper frame 10.

The lower bar of each head and foot frame 15 is produced beyond the ends and 110

is bent down as at 17, to form a stop which passing over the ends of the frame 10 retains the structure in the elevated position.

A strut 18 is pin-connected at 19 to each 5 end of the upper frame 10 and a pin 22 projecting outward from the other end of the strut is movable in a slot 20 in the longitudinals of the base frame 11, which slot has a notch 21 at its outer end into which 10 the pin 22 in the end of 18 falls when the frame is in the elevated position by which it is there retained.

Braces 23 are secured across the corners of the upper frame 10 to clear which braces 15 the cross members of the leg frames 12 are depressed, as shown in Fig. 2. Each end of the base frame 11 has an extension 24 which is upwardly turned to correspond approximately to the upwardly turned end 20 of the runway 7 and on each upwardly turned extension 24 is adjustably secured a portion 25 having a sheave or roller 26 rotatably mounted on a pin projecting from it.

25 These rollers 26 run in the end guideways 7, and enable the bed frame 10 when it is lowered on 11, to be moved backward beneath the front rail 3 of the couch. The upward offset of the end 25, which carries 30 the roller, is such in relation to the depth between the guideway 7 and the floor line, that when the front end of the frame is lifted clear of the floor, the frames 10, 11 may be moved backward and when drawn 35 out, the base frame 11 will rest on the floor.

To assist in this operation the guideways 7 have a slight upward rise a short distance from the front end.

To the underside of the front rail 3 a 40 plate 27 is secured, which plate projects beyond the inner edge of the rail and forms a ledge on which the front longitudinal of the bed frame may be lifted to keep it clear of the floor when the bed is moved beneath 45 the couch.

In order to facilitate withdrawal of the bed frame 10, 11 from its concealed position beneath the couch, and the return of the same, handles 28 are swivel and hinge 50 connected to the underside of the frame 10 at 29, (see Fig. 11). The horizontal portion of this handle 28 has an upwardly directed bend or prominence 30 immediately under the bed frame 11 to engage and lift 55 that frame to the ledge of the plate 27 before the handle encounters the underside of the front rail 3 of the couch, as shown in Fig. 11. When not in use, each handle 60 28 is turned on its swivel connection behind the rail 3, and may be supported on a pin 31 in the back of that rail, see Fig. 10.

The application of this bed extension requires but slight change from the existing construction of the usual Chesterfield couch, 65 viz, the re-upholstering of the seat provid-

ing removable cushions 6 in lieu of the customary seat upholstering, and the removal of the spring supporting webbing from the underside to the upper side of the rails 3, 4, 5 to provide space for the uplifting of 70 the bed frame to the concealed position. The improvement may, therefore, be readily applied to existing couches.

The construction of the bed frame is simple, although somewhat complicated to describe, and the slight additional cost is more than compensated in the convenience of the improved Chesterfield. 75

Having now particularly described our invention, we hereby declare that what we 80 claim as new and desire to be protected in by Letters Patent, is:

1. An improved Chesterfield bed, comprising the combination with a couch having an open rectangular frame including a front rail and being supported a short distance from the floor and upholstered to form a seat, a bed frame having supports at each end to sustain it at the required height to correspond with the couch seat 90 and collapsible on those supports to pass beneath the front rail of the couch frame, means for supporting the back corners of the bed frame when collapsed to the underside of the couch frame to be movable thereunder, and means for supporting the front of the bed frame from the underside of the couch frame when moved thereunder, said means being so constructed and arranged that no part of the collapsed bed frame 95 will project below the front rail so that the same is completely hidden from view and in a manner whereby the front face of the couch remains normal and undisturbed. 95

2. An improved Chesterfield bed, comprising the combination with a couch having an open rectangular frame including a front rail and being supported a short distance from the floor and upholstered to 100 form a seat, a rectangular bed frame having supports to sustain it at the required height to correspond with the couch seat and collapsible on those supports to pass beneath the front rail of the couch frame, means for supporting the back of the bed frame 105 when collapsed to the couch frame to be movable thereunder, and means for supporting the front of the bed frame from the front rail of the couch frame when moved 110 thereunder, said means being so constructed and arranged that no part of the collapsed bed frame will project below the front rail so that the same is completely hidden from view and in a manner whereby the front face of the couch remains normal and undisturbed. 115

3. An improved Chesterfield bed, comprising the combination with a couch having an open rectangular frame supported a short 120 distance from the floor and upholstered to 125 form a seat, a bed frame having supports to sustain it at the required height to correspond with the couch seat and collapsible on those supports to pass beneath the front rail of the couch frame, means for supporting the back of the bed frame when collapsed to the couch frame to be movable thereunder, and means for supporting the front of the bed frame from the front rail of the couch frame when moved 130 thereunder, said means being so constructed and arranged that no part of the collapsed bed frame will project below the front rail so that the same is completely hidden from view and in a manner whereby the front face of the couch remains normal and undisturbed. 135

4. An improved Chesterfield bed, comprising the combination with a couch having an open rectangular frame supported a short 140

- distance from the floor and upholstered to form the seat of the couch, a rectangular bed frame having supports at each end to sustain it at the required height to correspond 5 approximately with the couch seat and collapsible on those supports to pass beneath the front rail of the couch frame, members projecting backward from the ends of the bed frame, a wheel carried at the back end 10 of each backwardly projecting member, a track rail secured to the end rails of the couch frame adapted to receive the wheels of the bed frame, said track rails being inclined upward toward the back to lift the bed frame toward the couch frame when moved thereunder, means provided on the back of the front rail of the couch frame 15 for supporting the front rail of the bed frame in proximity therewith when moved 20 back and lifted.
4. An improved Chesterfield bed, comprising the combination with a couch having an open rectangular frame supported a short distance from the floor and upholstered to 25 form the seat of the couch, a bed frame comprising upper and lower rectangular frames, end supporting frames pivotally connected to the lower bed frame and slideable within the upper frame to engage and lift the same 30 when the end frames are moved to the upright position, head and foot frames pivotally connected to the upper ends of the support frames by which the same are erected, means for retaining the head and foot 35 frames from the ends of the upper bed frame when the end supports are in the erected position, a diagonal brace pivotally connected to each end of the upper bed frame and engaging a detent in the lower 40 bed frame when the end supports are upright, a wheel carried adjacent the end of a member projected backward from each end of the lower bed frame, a track secured to each end rail of the couch frame and 45 adapted to receive the wheels of each end of the bed frame, the back end of said track being inclined upward to lift the bed frame toward the couch frame, a support on the front rail of the couch frame to retain the 50 front of the bed frame, and means for lifting the front rail of the bed frame to and from that support.
5. An improved Chesterfield bed, comprising the combination with a couch having an 55 open rectangular frame supported a short distance from the floor and upholstered to form the seat of the couch, a bed frame comprising an upper and lower rectangular frame, the upper frame collapsible within 60 the lower frame, and supporting frames pivotally mounted to the ends of the lower rectangular frame and folding within it and susceptible of being raised to an upright 65 position to support the upper frame at a suitable height to conform to the seat of the couch, head and foot frames pivotally connected to the upper ends of the supporting frames to fold on the upper frame within its length and susceptible of being drawn upward and outward to erect the supporting frames, said head and foot frames having provision to engage the ends of the upper frames and retain the supporting frames in the erected position, a diagonal strut pivotally connected to each end of the upper 70 rectangular frame of the bed and slidably connected to the lower frame with a detent retaining the strut when the supporting frames are in the erected position, members projecting backward from the ends of the lower bed frame, a wheel mounted on each end of the backward projection, a guide rail secured to each end rail of the couch frame adapted to receive the wheel of the bed frame projection and permitting the bed 75 frame when collapsed to be movable under the front rail of the couch frame, said supporting rails inclined upward toward the back to lift the bed frame toward the couch frame when moved thereunder, means secured to the front rail of the couch frame and projecting backward therefrom to form a ledge to support the front edge of the bed frame, a handle pivotally and swivel connected to the upper rectangular frame of the bed and passing under the lower frame of the same for lifting the base frame of the bed on to the supporting ledge, and means on the front rail of the couch frame 80 for supporting the handle parallel with it 85 when not in use.
6. An improved Chesterfield bed, comprising the combination with a couch having an open rectangular frame including a front rail, legs supporting said frame from the floor, said couch being upholstered to form a flat seat, a removable flat bottom cushion on said seat, a foldable bed frame held above the floor a distance less than the height of the flat seat surface of the couch 90 equal to the thickness of the removable cushion, and adapted to receive said removable cushion to constitute an extension of said seat, said bed frame being foldable into a volume of a height and width to be passed 95 under the bottom of said rectangular frame between said legs, and means for holding said bed frame in the folded position within the confines of said rectangular frame 100 under the couch when said bed frame is not in use, said means being so constructed and arranged that no part of the collapsed bed frame will project below the front rail so that the same is completely hidden from view and in a manner whereby the front 105 face of the couch remains normal and undisturbed.
7. An improved Chesterfield bed, comprising the combination with a couch having a low positioned open rectangular frame sup- 110
- 115
- 120
- 125
- 130

ported a short distance from the floor and upholstered to provide a flat seat portion and a flat unbroken front, removable cushions cooperative with said flat seat, a rectangular extensible and foldable bed frame supported wholly by said couch frame when in the normal folded position, means whereby said bed frame may be extended so that the extended portion may rest wholly on the

floor, and other means whereby said bed frame may be vertically extended from its normal folded position to a height for supporting the removable cushions on a plane with the seat portion of the couch.

In testimony whereof we affix our signatures.

CHARLES OSCAR MORLOCK.
AXEL NORD.
